UNITED STATES PATENT OFFICE.

BERNARD RICE, OF NEW YORK, N. Y.

DESIGN FOR A BELT-PIN.

SPECIFICATION forming part of Design No. 25,770, dated July 14, 1896.

Application filed May 28, 1896. Serial No. 593,512. Term of patent 3½ years.

To all whom it may concern:

Be it known that I, BERNARD RICE, a citizen of the United States, residing in the city, county, and State of New York, have invented 5 and produced a new and original Design for Belt-Pins, of which the following is a specification.

In the accompanying drawings, Figure 1 is a front elevation of my design for belt-pins, 10 and Fig. 2 is a section thereof on line 2-2.

The leading feature of my design consists of a back bar of oblong shape and a cross-bar or loop centrally crossing the back bar, so as to form a cross.

15 A is the back bar, which has rounded-off ends a a, and B is the loop which crosses the back bar centrally thereof, so as to form a cross, in front elevation.

The central front portion of the loop B is formed with a forward curve or single corrugation b, while upon the same may be arranged, if desired, an ornament b', such as a flower, for instance a conventional fleur-de-lis, or any other ornament. 20

What I claim is—

25 The design for belt-pins, substantially as shown and described.

In testimony that I claim the foregoing as my invention I have signed my name in presence of two subscribing witnesses.

BERNARD RICE.
